US00D742707S

(12) **United States Design Patent**
Kundracik et al.

(10) **Patent No.:** US D742,707 S
(45) **Date of Patent:** ** Nov. 10, 2015

(54) **TOOL HEAD**

(71) Applicant: **Ridge Tool Company**, Elyria, OH (US)

(72) Inventors: **Richard M. Kundracik**, Elyria, OH (US); **Jason J. Boggs**, South Amherst, OH (US); **Prasad Patil**, Pune (IN)

(73) Assignee: **RIDGE TOOL COMPANY**, Elyria, OH (US)

(**) Term: **14 Years**

(21) Appl. No.: **29/486,349**

(22) Filed: **Mar. 28, 2014**

Related U.S. Application Data

(63) Continuation-in-part of application No. 14/202,611, filed on Mar. 10, 2014, which is a continuation-in-part of application No. 13/908,316, filed on Jun. 3, 2013.

(30) **Foreign Application Priority Data**

Apr. 1, 2013 (IN) 1263/MUM/2013

(51) **LOC (10) Cl.** **08-05**

(52) **U.S. Cl.**

CLAIM

(57) The ornamental design for a tool head, as shown and described.

DESCRIPTION

FIG. 1 is a rear left perspective view of a tool head.

FIG. 2 is a left side view of the tool head of FIG. 1.

FIG. 3 is a rear elevational view of the tool head of FIG. 1.

FIG. 4 is a right side view of the tool head of FIG. 1.

FIG. 5 is a front elevational view of the tool head of FIG. 1.

FIG. 6 is a top plan view of the tool head of FIG. 1; and,

FIG. 7 is a bottom view of the tool head of FIG. 1.

1 Claim, 7 Drawing Sheets
